Primary Examiner — Wan Laymon*Assistant Examiner* — Clint A Samuel(74) *Attorney, Agent, or Firm* — Novick, Kim & Lee, PLLC; Sang Ho Lee(57) **CLAIM**

We claim the ornamental design for a box for packaging, as shown and described.

DESCRIPTION

FIG. 1 is a perspective view of a box for packaging, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view showing the box for packaging in a configuration wherein a portion of the box for packaging is removed; and,

FIG. 9 is a perspective view showing the box for packaging in another configuration wherein a top portion of the box for packaging is in an open state.

The dash-dash broken lines shown in the drawings depict lines along which a portion of the box for packaging may be torn. The dot-dash broken line shown in FIG. 3 depicts a fold line.
